UNITED STATES PATENT OFFICE.

JOHANN LÜTZ, OF ESSEN-ON-THE-RUHR, GERMANY

MEANS FOR CONTINUOUSLY OPERATING COKE-OVENs.

1,236,727.

Specification of Letters Patent. Patented Aug. 14, 1917.

Application filed August 5, 1913. Serial No. 783,084.

To all whom it may concern:

Be it known that I, JOHANN LÜTZ, a citizen of the German Empire, and residing at Essen-on-the-Ruhr, Germany, have invented certain new and useful Improvements in Means for Continuously Operating Coke-Ovens, of which the following is a specification:

My invention relates to an improved process and apparatus for continuously working coke-ovens, in which the coke can slide in consequence of its own weight out of the chamber in the oven. In order to produce good coke, according to the invention the coke is removed periodically and, for the purpose of simplifying working and saving labor, by means of an automatic apparatus, the coal being supplied continuously in known manner to the coke-oven.

To these ends, the coke is removed as follows: The bottom of the oven is lowered into a casing closed air-tight and located adjacent to the oven, and the portion of the contents of the chamber which is to remain in the chamber is supported by a supporting or clamping device able to be thrown into operation. The bottom is then lowered still further, the coke located on it is removed through a lateral opening in the casing, the bottom is then raised and the supporting device cut out of operation. In order to do this automatically the bottom is preferably lowered slowly and continuously until the supporting device is thrown in. The requisite carbonizing period is hereby assured and the moved bottom can itself throw into gear the driving mechanism for throwing in the supporting device and for lowering the bottom still further.

The additional driving devices for carrying out the emptying of the oven can likewise be thrown into and out of operation by the moved members, so that completely automatic working results. When the plant is driven hydraulically, cocks are opened and closed in a predetermined order by the moved parts. The slow continuous lowering of the bottom is then preferably effected by water being continuously run off through regulatable nozzles from cylinders containing the rams carrying the bottom.

A coke-oven adapted for carrying my improved process into practice is made, for example, as follows: The bottom is so arranged in an air-tight casing connected to the lower end of the coking chamber that it

can be bodily shifted and rotated. The casing has a lateral discharge outlet and a deflector arranged close to it consisting of a pivotally mounted plate which when out of use is located in a recess in the casing and can be so adjusted that when the bottom of the oven rotates, the coke is pushed through the outlet. At the lower end of the coking chamber are arranged water-cooled fire-bars which can be inserted from the outside into the caked coke in the oven, so that the coke is supported when the bottom is lowered with the coke located between it and the fire-bars.

One form of coke-oven whose coking chamber is formed as a vertical annular chamber is represented by way of example in the accompanying drawing, wherein:

Figure 1 is a vertical section through the coke-oven;

Fig. 2 is a vertical section of the controlling mechanism;

Fig. 3 is a vertical section of the apparatus for carrying away the quenched coke;

Fig. 4 is a section taken on the line F—K in Fig. 5;

Fig. 5 is a plan view of the controlling apparatus; and

Figs. 6 and 7 are respectively an elevation and a plan of the controlling mechanism.

Referring to the drawings, the coal is supplied to the annular coking chamber *a* from the hopper *b* by way of the drums *c* without gas being able to escape through the latter. The coal slides down the chute *d* into the chamber *a*, while the gas escapes between the chute and the walls of the chamber *a*.

At the lower end of the chamber *a* is arranged the casing *e*, a gas-tight joint being provided between the two portions of the double wall; this casing surrounds the bottom *g* of the oven which rests on the hydraulic rams *f* connected by pipes *f'* provided with a supply and discharge pipe 14 having a supply valve 14, and discharge valve 12, and an adjustable control or escape nozzle 24; and can rotate on the rollers *h*.

Referring now to Figs. 2 to 7, which diagrammatically show the controlling mechanism for automatically emptying the bottom, the parts in these figures are shown in that position in which the bottom *g* located in its lowest position is being rotated, and the deflector *l* and scraping belt *n* are operating.

Assuming that the rams *f* and the bottom

are at their uppermost position, and the process of coking begun, they now descend with the entire charge in the oven carried by them at a very low speed, preferably 5-7 mm. per minute, corresponding to the rate at which the coking proceeds. To this end the adjustable escape or control nozzle 24 of the cylinder of the rams is adjusted to the suitable speed of descent and remains 10 constantly in this position, allowing a small jet of water to issue therefrom. After the bottom has descended a certain distance, e.g. 1000 mm., the stop lever 25 carried by the member 50 provided at the lower end of the 15 connecting member 51, which is secured to the upper end of the ram *f* at 52 and descends therewith, abuts against the lever 26, moving the same from the position shown in dotted lines to that shown in full lines in 20 Fig. 6, whereby a three-way cock 17 is actuated. This cock 17 is connected by a pipe 17^a to the horizontal ram 53 of the hydraulic fire bars or grate *i*, the said pipe 17^a being shown broken away in Fig. 7 and connected 25 to the ram 53 in Fig. 1. The grate preferably comprises water-cooled bars, and the opening of valve 17 causes water to flow behind the ram 53 and the grate to be inserted into the chamber, so that the contents of the 30 chamber are supported thereon. During the descent of the rams *f*, the weighted cock 20, which is also connected to the rams 53 by means of a pipe 20^a, is actuated by its weight, and causes the water in front of the 35 ram to flow therefrom so that when the cock 17 is actuated, the grate is inserted with a relatively quick action. The charge in the oven is supported by the grate *i*, while the bottom descends gradually with the layer of 40 coke 1000 mm. thick by reason of the slow discharge through the escape nozzle 24. The stop lever 21 also carried by the member 50, now actuates the lever 29, which opens the discharge cock 12 connected to the rams *f* 45 by the three-way pipe 14^a above referred to, one part of which extends to the cock 12, one to the connecting pipe *f* of the rams, and the other to the supply cock 14, so that the water is discharged more quickly than 50 through the regulated escape nozzle 24, the valve 12 being entirely open, and the bottom can now descend rapidly to the end of its stroke, the hydraulic grate *i* now being closed or inserted and supporting the coke 55 in the chamber. The lever stops 21 and 25 are so constructed as to be rigid when engaged at their under sides, and pivotal when engaged at their upper sides, so that they are inoperative during upward movement of 60 the rams. Shortly before the lower end is reached, the lever 27 carried at the upper end of the ram *f* presses down the lever 28, whereby the cocks 3, 4, 5 and 6 are actuated, so that the cocks 4 and 5 are opened and 65 the cocks 3 and 6 are closed, the said cocks 3 and 4, and 4 and 5 being connected respectively in front of and behind the piston of the ram *g* by means of pipes 54 and 55. Inlet and outlet pipes 56 and 57 are provided to the said cocks. The piston rod 58 of the 70 ram *g* now operates, being moved from the dotted line position shown in Figs. 5 and 6 to the full line position, throwing the deflector 1 into position across the path of the bottom *g*, by means of the lever 58^a connected to the rod by a wrist pin 58^b. The deflector when not in use is located in a recess in the inner wall of the casing. The stop 7 carried by the rod 58 actuates the levers 8 and 9, which are respectively connected by members 59 and 60 to the driving belts 61 and 62, which are moved from inoperative position on the idle pulleys 63 and 64 to operative position on the driving pulleys 65 and 66, whereby the bottom *g* is rotated 75 with respect to the deflector 1, and the scraping belt *n* is brought into operation. The coke is deflected by means of the deflector 1 through the lateral outlet *k* into the trough *m*, filled with water, from which it is removed by the scraping belt *n* over the grate *o* to a conveyer device. 80

The fine particles of the coke can fall into the chamber *p* arranged beneath the grate *o*, from which they can be removed from time to time. 85

During the first revolution of the bottom *g*, a stop or projection 1^a carried thereby strikes against the legs of the lever 2, and revolves it through an arc of 45°, actuating the cocks 3, 4, 5 and 6, so that the positive action of the ram *g* is stopped and the same placed in condition for the reverse action. The bottom *g* is preferably allowed to rotate twice so that all the coke will be effectively 90 removed. When the stop 1^a, during the second revolution of the bottom *g*, strikes the next finger 2^a, it is again rocked through an arc of 45° and reverses the position of the cocks 3, 4, 5 and 6. The cock 3 is opened 100 and allows water to enter behind the piston of the controlling ram *g*. The cock 4 which controls the outlet of water from behind the piston is closed, as well as the cock 5 which supplies water in front of the piston, and the cock 6 which allows the water in front of the piston to run off is opened. The ram *g* now shifts the deflector 7 into its rest position shown in dotted lines in Fig. 7; the stop 7 on the piston rod 58 strikes 110 against the levers 8 and 9 and disconnects the driving gear of the bottom *g* and the scraping belt *n*. A stop 10 also carried by the rod 58, and so constructed as to be rigid during the outward movement of the rod 115 and pivotal during the inward movement, engages the lever 11, reversing the discharge cock 12 and the lever 13, which opens the supply cock 14, which controls, through the pipe 14^a, the hydraulic rams *f*, and the latter 120

130

rise with the bottom to close under the grate *i*.

Toward the end of the upward movement of the rams *f* a stop 15 carried by the member 50 lifts the lever 16, which is connected by a member 67 with the lever 26, and reverses the three-way valve 17, so that water, which has driven the grate *i*, can flow out, and a stop 18, also carried by the member 50, simultaneously lifts the weighted lever 19 and reverses the three-way cock 20, so that water is supplied behind the ram of the hydraulic grate and the latter is retracted. At the end of the stroke the stop lever 21 disconnects the rod 23 having a weighted catch member 71, by means of the catch 22 and the supply cock 14 is again closed, cutting off the supply of water to the hydraulic rams *f*. The rams and bottom *g* have now reached their highest position, and the cycle of operation at once begins again, because of the slow issuance of water through the constantly open nozzles 24, from the cylinders of the rams *f*.

I have illustrated and described a preferred and satisfactory form of my invention, but it is obvious that changes may be made therein within the spirit and scope thereof as defined in the appended claims.

I claim:

1. A coke-oven, comprising a vertical coking chamber having a vertically displaceable bottom, means for feeding coal into said coking chamber, means for automatically lowering said movable bottom at a predetermined speed, while said coal is fed into said coking chamber, and holding means auxiliary to said bottom for receiving and supporting the coal fed into said coking chamber after said movable bottom has been moved a predetermined distance, said auxiliary holding means being automatically placed into action after said movable bottom has been lowered a predetermined distance.

2. A coke-over, comprising a coke chamber having a vertically displaceable bottom, means for feeding coal into said coking chamber, means for automatically lowering said movable bottom at a predetermined speed while the coal is being fed into said coking chamber, and means for automatically removing the coke at the said bottom of the said coking chamber, after said bottom has been lowered a predetermined distance.

2. A coke-over, comprising a coke chamber having a vertically displaceable bottom, means for feeding coal into said coking chamber, means for automatically lowering said movable bottom at a predetermined speed while the coal is being fed into said coking chamber, and means for automatically removing the coke at the said bottom of the said coking chamber, after said bottom has been lowered a predetermined distance.

3. In a coking-oven, a vertical coking chamber, having a vertically displaceable bottom, and means for moving said bottom at a predetermined speed, and means for separating said coke to permit a portion of the same to be lowered with the bottom, and the remainder to remain stationary in the chamber.

4. In a coking oven, a vertical coking chamber having a vertically displaceable bottom, and means for moving said bottom at a predetermined speed, and means for separating the coke to permit a portion of the same to be lowered with the bottom, and the remainder to remain stationary in the chamber, and means for automatically moving said bottom at an increased speed after the separation of the said coke.

In testimony whereof, I have signed my name to this specification in the presence of two witnesses.

JOHANN LÜTZ. [L.S.]
